UNITED STATES PATENT OFFICE

OVE PETERSEN, OF HELLERUP, NEAR COPENHAGEN, DENMARK

REVERSING GEAR FOR INTERNAL COMBUSTION ENGINES

Application filed June 29, 1928, Serial No. 289,311, and in Denmark July 13, 1927.

This invention relates to a reversing gear for combustion engines of that kind in which the fuel is injected into the cylinder without employing compressed air injection, only by the pressure of a pump, the motion of which is governed in a well regulated way relatively to the piston stroke of the engine by a reversible cam device or the like. The invention has for its object to produce a simple and securely acting reversing gear, by which the reversing of the fuel oil pump is effected in the most simple way, and where the fuel pump mechanism is, at the same time, relieved from the pressure of the fluid fuel during the period in which the motion is reversed from forward to back or vice versa. The invention is chiefly characterized in that the cam roller determining the motion of the fuel pump is during the reversal raised, clear of the cams in a direction which is chiefly identical with its normal direction, whereby in order to relieve the fuel pump mechanism from the pressure of the fluid fuel during this period a device is provided for, which is moved from the starting handle of the engine, the relief being brought about when the starting handle is moved into the stop position, so that the piston of the fuel pump may be moved inwardly without any resistance from the pressure of the fluid fuel. According to the invention the starting lever is preferably so connected with the reversing shaft that they lock each other, so that the rotation of the latter is only possible in one position of the starting handle viz. the stop position, whereby is obtained that the relief of the fuel oil pump mechanism is brought about before the manœuvring shaft can be rotated, while on the other hand the starting handle can be moved out of its stop position only in one position of the manœuvring shaft, viz in that position where the cam roller is in connection with the cam for forward or back motion. The relief in itself is effected thereby that the suction valve, overflow-valve, slide or the like of the fuel pump, or another valve, slide or the like in the pressure pipe system of the fuel pump is opened and kept open during the reversal period, the actuation of the said relieving member issuing from a device, which is moved thereby that the starting handle is moved into its stop position. The invention brings the essential mechanical advantage that the crew need not move any special handle to relieve the fuel pump by the reversal, so that full security is obtained that the elements by which the reversal of the fuel pump is carried out are not exposed to having to overcome the pressure of the fluid fuel, which is very high in machines with atomization by pressure. The invention further relates to various preferred devices combined with the reversing means in question. The invention is illustrated in the drawings, which show various constructional forms of the reversing gear. Fig. 1 is a perspective view of a constructional form employed in reversible engines of the type in which all of the valve levers are eccentrically mounted on one shaft, Fig. 2 shows parts of the same in elevation and on a larger scale, Fig. 3 is a perspective view of a reversing mechanism and a manipulating lever or handle cooperating therewith, and a diagrammatic view, partly in section, of a fuel pump and a mechanism provided between the pump and the manipulating mechanism serving to relieve the pump from the oil pressure, Fig. 4 shows a constructional form of the actuating means of the fuel pump in elevation, Fig. 5 part of the same, as looking from the left side in Fig. 4, Fig. 6 another part of the same, on a smaller scale, as seen from the right side in Fig. 4, Fig. 7 is a perspective view of a constructional form of a reversing gear in a motor of that type in which all of the valve levers are concentrically mounted on one shaft and actuated by push rods, Fig. 8 is a perspective view on a larger scale of a modified constructional form of part of the gear, Fig. 9 shows a constructional form of the reversing gear according to the invention capable of being employed both in engines with all valve levers mounted eccentrically on one shaft and in engines having all valve levers mounted concentrically and actuated by push rods, and Fig. 10 is a diagrammatic view of a constructional form of part of the gear. In the reversing gear shown in Fig. 1 all of the valve levers are

eccentrically mounted on one shaft, the rotation of which causes the rollers on the valve levers to be raised clear of the cams of the cam shaft discs, the reversing being carried out by the cam shaft being displaced longitudinally, in such way that the forward and back cams are brought into positions opposite their respective valve levers. 1 indicates the common reversing shaft carrying the eccentricities 2, 3, 4, which again carry the valve levers 5, 6, 7, and from which the admission valve, exhaust valve and starting valve, respectively, are actuated, the rollers being actuated either from the cams 8, 9, 10 for forward motion or from the cams 11, 12, 13 for back motion. The said cam discs are mounted on the rotating cam shaft 14, which is driven in a known way from the engine crank shaft. In a reversing gear according to the present invention the shaft 1 further carries an eccentric 15 provided with a lever 16, whose roller 17 follows a cam disc 18_a for forward motion (as shown in the drawings) or a cam disc 18_b for back motion when the shaft 14 has been displaced longitudinally in the direction of the arrow far enough to place the said disc 18_b opposite the roller 17. That end of the lever 16 remote from the shaft 1 is provided with a roller 19 serving to actuate the fuel oil pump. 20 indicates the housing of the oil pump, 21 the pump plunger, which is provided at its bottom end with a head 22_a. A spring 23 is inserted between the pump housing 20 and said head 22_a, serving to keep the pump plunger in engagement with the roller 19, the pump plunger being thereby forced to follow the motion of the roller and in this way also the motion imparted to the lever 16 from the cam disc 18_a or 18_b. Below the roller 19 a fixed stop 22_b secured to the engine frame is provided, adjusted in such a way that when the roller 17 is out of engagement with the cam portion of the cam disc 18_a or 18_b some slight amount of clearance 24 is present between the roller 17 and the cylindrical portion of the cam 18_a or 18_b. When the engine is running either forward or back, the position of the reversing shaft 1 is such that the eccentric portion of all eccentricities 2, 3, 4, 15 is pointing downwards or nearly so, so that all rollers of levers 5, 6, 7, 16 are actuated by the cams. During the reversing operations the shaft 1 is rotated to such an extent that the centres of all eccentricities are moved upwards into a position vertical above the first described position. This causes the rollers of the valve levers to be raised out of engagement with the cams in the well-known manner. With regard to the lever 16 actuating the fuel oil pump this lever is raised by means of the fixed stop 22_b, and it will then occupy the position shown in Fig. 2 with the eccentric 15 turned over so that it points upwards. In this position roller 19 at the extreme end of

lever 16 rests against or is supported by the fixed stop 22_b, and the roller 17 is thus raised to such an extent as to clear the top of the curve 18_a of the cam 18_a, the pump plunger 21 of the fuel oil pump 20 being in its lowermost position with its head 22_a resting against the roller 19. In this position of the reversing shaft 1, as mentioned above, the rollers of all valve levers also clear the cams of the cam shaft and accordingly the cam shaft may now be displaced in a known manner, so that the cams corresponding to the opposite direction of rotation are placed in position to engage the rollers. After this the rotation of the reversing shaft 1 is continued so as to make the eccentricities point downwards instead of upwards, whereby the rollers are moved into working position in relation to the cams now serving as actuating cams. Considering now more particularly the reversing mechanism or apparatus of the fuel oil pump it will be seen that during the movement of the roller 17 into the working position the rotation of the reversing shaft 1 will cause the pump piston to be pushed into the pump housing 20, if the engine is so positioned that the curve of the cam 18_b is located exactly under the roller, thus causing a pressure stroke to be made. This would result in a very considerable stress on the reversing apparatus, because pressures between 200 and 500 atmospheres are employed in such engines. According to the invention this occurrence is prevented by a suction valve, bypass valve, slide or the like situated in the pressure piping of the pump being connected with the starting handle in such way that the said valve or the like is always kept open during the reversing operations. For this starting arrangement it is assumed that the internal combustion engine is adjusted in a known manner by compressed air and the reversing mechanism is set similarly in a known manner either by hand power, by compressed air, or by some other force. An example of a reversing mechanism of this kind is shown in Fig. 3.

The reversing shaft 1 carries a helical cam 25 of a known kind engaging two collars 25_a and 25_b on the shaft 14, so that the latter is displaced in its longitudinal direction, when the shaft 1 is rotated e. g. 360°. The shaft 1 carries also a worm wheel 26 engaging a worm 26₁ mounted on a shaft 28 which carries also a motor 27 and at its lower end another worm 30 engaging a worm wheel 30₁ mounted on a shaft 135. This shaft carries also a gear wheel 120 engaging a gear wheel 121 the diameter of which is twice as great. The gear wheel 121 carries an eccentric pin 122 on which is loosely pivoted a sliding block 123 sliding in a frame 124 which forms the upper end of a cylindrical rod 125. This rod is guided further down by a bearing 126 so as to be bound to move vertically up and down.

At its lower end the rod 125 carries a flat block 127 with a recess 128. 29 is a reversing handle by which the motor 27 may be started and which carries a projection 129 projecting into the recess 128. By means of this recess and the motion carried out by the block during the reversing period a control and partly locking of the motion of the handle 29 is effected as will appear from the following:

10 In the shown position of the handle 29 this is in its central position, and the cam shaft of the internal combustion engine is supposed to be adjusted for forward running. If the engine is to be reversed this is effected thereby that the handle 29 is moved into one or the other of the positions B or F, the extension 130 of the handle 29 closing hereby one or the other of the contacts 131, 132; so as to close an electrical current to the motor 27, the supply of current taking place through two main poles 133. The drawing shows that the handle 29 can only be moved to the left, i. e. to the position B, motion to the right being prevented by the right side of 20 the recess 128. The motion to the left corresponds just to reversal for backwards running and causes by the closing of the contact 131 that the motor starts. Hereby the gear wheel 120 is rotated one revolution by the worm gear 30, 30₁, while the gear wheel 121 is rotated half a revolution, and the projection 122, which is shown in its uppermost position in the drawing, is hereby carried into its lowermost position. During this motion 30 the sliding block 123 carries along the frame 124, guiding rod 125 and block 127, and the inclined left wall of the recess 128 presses then against the projection 129 of the handle 29 so as to move the latter into its central 35 position. When this position is reached, the electrical current is cut off and the motor 27 stops. In the new position of the block 127 the recess 128 allows only the motion of the handle 29 from central position to the right, i. e. to the position F, which corresponds thereto that the internal combustion engine, which is now reversed to backward running, is now able only to be reversed to forward running. The device thus acts in a manner 40 corresponding fully to that described above only with the difference that the block 127 is moved upward and the inclined right wall of the recess 128 carries the handle back into its central position by pressing against the 45 projection 129.

The starting itself of the combustion engine is effected by a starting handle 32 shown in full lines in its stop position. The starting is effected in a known manner by compressed air when the handle 32 is moved to the position 32₁ (starting position).

According to the invention the fuel pump is provided with an overflow valve 33 serving to connect the pressure pipe of the pump 60 with an outlet pipe 34, through which the

oil in the pump is returned e. g. to the fuel oil tank, when the valve 33 opens. The valve 33 is moved up and down by a lever 35 receiving its motion from the fuel oil pump plunger 21, which again receives its motion 70 in a known manner from a cam mechanism, a link gear or the like (not shown in the drawings), the lever 35 being pivoted on an eccentric 36. This eccentric enables the position of the axis of rotation of the lever 35 to be 75 moved up and down by moving the lever 37 up and down. By adjustment of the lever 37 it is possible to keep the valve 33 raised above its seat during the complete stroke, so that no fuel is delivered to the engine. 80 According to the invention the said lever 37 is connected to the starting handle 32 by a rod 38, which again is connected with the handle 32 by a lever 39, the adjustment of the rod 38 being such that the valve 33 is 85 raised from its seat during the entire stroke of the fuel oil pump, when the starting handle is in any of the two positions 32 and 32₁, shown in the drawings or in any position intermediary thereto. The motion of the starting handle 32 is interlocked with that of the reversing handle 29 in such a way by a disc 31 that the handle 32 is only capable of being moved from the stop position (shown in full lines) into the position 32₁ (by which movement the engine is started by means of compressed air), when the disc 31 is in such a position that the reversing gear is either in its extreme forward position or in its extreme 90 back position, because in any of these positions the notch 31₁, provided in the disc 31 is opposite the projection 40 of the starting handle 32. In a similar way the handle 29, and thus also the motion of the reversing gear, is secured or locked in relation to the 95 position occupied by the starting handle 32, so that the handle 29 may only be moved in order to start the reversing gear from one position to the other when the handle 32 is 100 in its stop position, whereby the valve 33 in all positions of the internal combustion engine is raised from its seat, so that the fuel oil pump is completely relieved of pressure.

Fig. 4 shows a constructional form of the actuating mechanism of the fuel oil pump. 1 115 is the reversing shaft on which the lever 16 actuating the fuel oil pump is mounted, this lever being provided with the roller 17 which receives its motion from the cam 18. The lever 16 extends beyond the roller 17 and carries at its extreme end two rods 52 connected at their bottom ends by means of a cross-head 51, on which the pump plunger 21 is mounted. Fig. 6 shows this connection for the fuel oil pump in end view, showing the end of the lever 16, the two rods 52 and between these latter the cross-head 51 carrying the pump plunger 21 working within the fuel pump housing. Contrary to the above 120 described constructional form the fuel pump 130

in the present form is rigidly connected to the lever 16. The rods 52 have intentionally been so chosen and arranged that the pump will subject them to tension during the pressure stroke, in this way these rods may be made of small diameter and great length, so that the side pressure on the plunger, which in these engines must necessarily work with an extraordinarily small amount of play, becomes extremely small, and thus the pump plunger is prevented from seizing in the pump housing. The fuel oil pump is not provided with a helical spring as in the previously described constructional form, but the lever 16 is extended beyond the axis of rotation of the shaft 1 (see Fig. 4), thus presenting a double lever. At its extreme end it is provided with a head 41 with an hour-glass-shaped hole 42, thus leaving free passage for a rod 43. This rod 43 is at its extreme end rotatably mounted in a fixed bearing or the like. The rod carries a fixed stop in the shape of a disc 45, and a spring 46 is inserted between this disc 45 and the top-piece 47 which serves as a spring-seat. Fig. 5 shows the head 41, tension rod 43, helical spring 46, and top-piece 47, as seen from the end of the lever. The top-piece 47 is provided with two pivots 48, from which two tension rods 49 extend downwards without touching the fixed stop 45, to another two journals 50 mounted on each side of the head 41. The tension rod 43 is so long that it passes freely through a hole provided in the spring seat 47, which ensures sufficient stability of this arrangement. The adjusting mechanism is now so constructed that the roller 17 has a sufficient slight amount of play 24 in relation to the cam 18_a, when the spring 46, by exerting pressure on the spring seat 47 through the tension rods 49, draws the head 41 of the lever 16 up towards the fixed stop disc 45 on the rod 43, which corresponds to the fuel oil pump plunger 21 being in its bottom position. During reversing operations, in which the shaft 1 is so rotated that the eccentric 15 is moved into its topmost position, the roller 17 will be lifted clear of the curve 18_a of the cam 18_a, so that the displacement or shifting of the cam shaft may be effected, the pump plunger being at the same time moved upwards into its uppermost position, which meets with no resistance, as the by-pass valve or the like is open as described above; further, this movement is effected with the least possible resistance, because the arrangement of the spring, as described above, makes it unnecessary to compress the spring, as the rotation is effected while the head 41 of the valve lever 16 is supported by the fixed stop 45 of the tension rod 43. It is thus obtained that the reversing of the fuel oil pump takes place with the least possible resistance, inasmuch as the pump is not only relieved of pressure but also

of the spring tension. As mentioned above, the constructional form of the reversing gear according to the invention as shown in Fig. 7 is intended for reversible internal combustion engines of the known type in which all the valve levers are pivotally mounted on one fixed shaft and driven by push rods from cam discs on a cam shaft, the push rods being swung free of the cams during reversing operation. 1 is the fixed common shaft on which the valve levers 5, 6, 7 are pivoted, and 53, 54, 55 are the corresponding push rods for admission, starting, and exhaust valves respectively. At their bottom ends the push rods are hinged to links 58, 59, 60 pivotally mounted on the crank 57 of the reversing shaft 56. Vertically below the push rods 53, 54, 55 the links 58, 59, 60 carry cam rollers engaging the cams 8, 9, 10 for forward motion or 11, 12, 13 for back motion, of which latter only 12 and 13 are visible in the drawings. These cams, which are mounted on the cam shaft 14, rotate during the running of the engine, driven from the crank shaft of the engine by a suitable gear. A reversing shaft 56, which is parallel to the cam shaft 14, is shown in Fig. 7 in the position in that the crank 57 is next to the cam shaft 14, in which position the cam rollers engage one set of cams. If the engine is to be reversed, this is done manually, by compressed air or by some other power in a similar manner as described for engines with eccentrically mounted valve levers. The reversing shaft 56 is rotated in total 360° from the position shown in Fig. 7. During the first part of this rotation the link rods 58, 59, 60 will draw the cam rollers away from the cams on shaft 14, and the valve levers 5, 6, 7 being kept by suitable means, the push rods 53, 54, 55 will swing out as pendulums suspended in fixed points, viz. their points of union with the valve levers 5, 6, 7. When the cam rollers have got clear of the cams, the cam shaft 14 is displaced longitudinally as far as necessary for the cam rollers to engage the cams corresponding to the opposite direction of rotation, when the push bars are swung back into their initial position by the continued rotation of the reversing shaft 56. The cam shaft 14 carries also the cams 18_a and 18_b, serving to move the fuel pump piston and corresponding to forward and back motion respectively, one of which cams engages during the running of the engine a cam roller 61 on a lever 62 mounted on a fixed pivot 63. The lever 62 treads with a roller 64 on the flat head 65 of the fuel pump piston 21, said head being pressed against the roller by a helical spring 23, which causes the outward stroke of the piston 21. This piston 21 works in the fuel pump, the house 20 of which is rigidly mounted in the engine. An eccentric or cam 66 mounted on the reversing shaft 56 engages an arm 67 on the lever 62. In the

position of the reversing shaft 56 shown in Fig. 7 the disc 66 is without influence on the motion of the lever 62, this motion during the running of the engine being caused only by the cam 18_a or 18_b with which the cam 5 roller 61 engages. To the fuel pump mechanism belongs further a lever 69, one end of which is rotatably mounted on a pivot 70 on the pump plunger head 65, while its other end is pivoted by a tension rod 71 to the arm 10 39 of the starting handle 32. In the rod 69 the overflow slide 68 is rotatably suspended. This slide controls a by-pass in the fuel pump in such a way that following the motion of the pump plunger 21 during the working of 15 the engine it opens the by-pass at the end of each pump stroke, thus bringing the fuel injection to an end. During the first part of the reversing operations, where the reversing shaft is, as described above, rotated 360°, 20 the cam 66 pushes the piston 21 to the bottom of its stroke through the arm 67, lever 62 and roller 64. If during this motion the pump pumped fuel oil into the motor cylinder, there would be a very great resistance 25 against the rotation of the reversing shaft and the motion of the members connected therewith. According to the invention the fuel pump is relieved from this pump pressure during the reversal, the overflow slide 30 68 being so far displaced downwards by the starting handle 32, lever 39 and tension rod 71 before the rotation of the reversing shaft 56 that already at the beginning of the downward motion of the pump plunger caused by the rotation of the reversing shaft the by-pass is opened, so that during this downward motion the pump plunger 21 has to work only against the insignificant counter-pressure in the by-pass. Simultaneously with the downward motion of the plunger 21 the slide 68 is moved further downward owing to its connection with the lever 69, which will, however, only cause the by-pass to be kept open 40 still. Similarly to what has been described above with regard to engines with eccentrically mounted levers, the handle 32 is locked in such a way that it cannot be moved until the reversing mechanism is in position either 45 for forward or for back movement, and the said reversing mechanism is similarly locked in relation to the handle 32, so that it cannot be moved until the handle is in its stop position, in which the fuel pump is relieved as 50 already stated. A modification of the arrangement represented in Fig. 7 is shown in Fig. 8, in which 18_a and 18_b, as above indicate the cams for forward and back motion with 55 regard to the motion of the fuel pump plunger. These cams cooperate with the roller 61 on the lever 62, whose axis of rotation is not stationary as in the arrangement shown in Fig. 7, but may change position, because the lever 62 is rotatably mounted on an eccentric 60 72 on a shaft 73 mounted in two stationary 65 bearings 74, 75. The lever 62 carries two pivots 76 engaging the eyes of tension rods 77. These rods 77 are at the top hinged to two governing rods 78 sliding in fixed guiding members 79 extending from the fixed 70 pump housing 20. The guide rods 78 are connected with a cross-head 80 carrying the pump plunger 21. The lever 62 is a double lever and is provided, similarly to the lever 16 in Fig. 4, with a head 41 with an hour-glass-shaped hole 42, wherein is mounted a tension rod 43, which may pass freely through the hole 42. At its lower end the tension rod 43 is pivoted to a fixed bearing 44 or the like 75 and provided with a stop 45 secured to the 80 rod 43. The head 41 is pressed against this stop by the pressure of a spring 46 placed between the stop 45 and a spring seat 47 having two pivots 48, which are connected by two tension rods 49 with two pivots 50 extending from the head 41 of the lever 62. The pressure of the compressed spring 46 forces the roller 61 to follow during the working of the engine the cam 18_a or 18_b, while on the contrary the roller 61 has no contact with 90 the cylindrical portion of the cam, the stop 45 or the push rod 43 being so disposed that a very small play exists between the cam roller 61 and the cylindrical portion of the cam 18_a or 18_b, when the head 41 of the lever 95 62 is pressed against the stop 45. The shaft 73 carries a lever 81, which by means of a tension rod 82 is connected with an eccentric strap 83 surrounding an eccentric 100 84 mounted on the reversing shaft 56. The position of the eccentric 84 on the reversing shaft 56 is such that a rotation of the latter causing the rollers on rods 53, 54, 55, Fig. 7, to go free of the cams on the cam shaft 14 causes at the same time the eccentric 105 72 to leave the position in Fig. 8, where the eccentricity points upwards. The rotation of the reversing shaft thus causes the axis of rotation of the lever 62 to be lowered, and as the head 41 of the lever rests on the fixed 110 stop 45, the lever 62 is turned downwards so as to remove the roller 61 from cams 18_a, 18_b. At the same time the pump plunger is pushed inwardly to its innermost position, and during this manoeuvre the pump is relieved from the pressure of the fuel oil by a slide 68 or the like in a similar manner as 115 described with regard to Fig. 7. The advantage of the last described constructional form as compared with that of Fig. 7 is that the movement of the pump piston down to the bottom position does not require any compression of the spring, in this case the helical spring 46, normally causing the downward motion of the pump plunger and pressing 120 the cam roller 61 against the cam 18_a or 18_b, the pressure of the spring 46 on the lever 62 in the said device acting in a direction passing through the point of contact between the head 41 and fixed stop 45. The slide 68 is 125 130

so mounted in the cross-head 80 that it is bound to follow its motion up and down, whereas it may rotate freely around its own axis. The slide 68 has an arm 168, which is bound by a key connection to take part in the rotation of the slide around its axis, whereas the lever 168 need not follow the up and down movement of the slide. Connected with the lever 168 is a tension rod 68¹ connected with the starting and regulating handle of the engine (not shown in Fig. 8) by a link connection, so that the slide 68 uncovers in a similar manner as according to Fig. 7 an overflow, when the starting handle is in its start or stop position. In the constructional form of the invention shown in Fig. 9, which is employable both in reversible combustion engines having all the valve levers mounted eccentrically on one shaft and in reversible combustion engines having the valve levers mounted rotatable around a fixed shaft and moved by push rods, 14 is the cam shaft with cams 8, 9, 10 and 11, 12, 13 for forward and back motion and for the valve levers for admission, exhaust and starting valves respectively. Mounted on the cam shaft 14 is a spur gear 85 meshing with another spur gear 86 on a cam shaft 114, on which the cams for one or more fuel oil pumps are mounted. Three sets of cams are shown in the figure, of which cams 18_a are for forward, cams 18_b for back. Opposite each set of cams is a lever 62. The levers 62 are actuated by the cams through the rollers 61 and mounted on pivots 63 rigidly mounted in relation to the engine. The levers 62 carry rollers 64 held against the flat heads 65 of the respective fuel oil pump plungers 21, which plungers 21 work within the fuel pump housing 20. The head 65 is pressed against the rollers 64 by the helical springs 23. Parallel to the cam shaft 114 is a reversing shaft 156 provided with levers 166, which may engage the projecting arms 67 on levers 62. The cam shaft 114 for the fuel oil pump is longitudinally displaceable in its bearings 87, 88 and is provided with two fixed collars 89, 90 enclosing a shoe having two pivots 91, which are held by the branches 93 of a forked lever 92. The cam shaft 14 has similarly two fixed collars 95, 96 enclosing a shoe with two pivots 94 also mounted in the branches 93 of lever 92. The lever 92 is rotatable on an axle or a pivot 97 in the engine. By this arrangement, which forms a connection between the shafts 114 and 14, is obtained that the cam shaft 114 for the fuel oil pump is moved in the same manner and at the same time as the cam shaft 14 for the valves of the combustion engine, when the latter shaft is longitudinally displaced during the reversal, only with the difference that the movements of the shaft 114 are a little greater than those of the shaft 14. The cams 18_a for forward and 18_b for back motion thus are shifted in such a way that one or the other

set of cams respectively are brought into engagement with the rollers 61 on levers 62 for the fuel oil pump motion. The reversing shaft 156 for the fuel oil pump motion is provided with a lever 98 connected by a rod 99 with an eccentric 100, this eccentric being mounted either on the common reversing shaft 1 for the valve levers (which applies to internal combustion engines with valve levers mounted eccentrically on one shaft) or on the reversing shaft 56 (which applies to internal combustion engines in which the valve levers are rotatably suspended on a fixed common shaft and actuated by push rods). By rotation of the shaft in question 1 or 56, whereby the rest of the reversing gear of the internal combustion engine is set for forward or back respectively, the shaft 156 is rotated through a corresponding angle, so that levers 166 engage the projecting arms 67, thereby pressing these arms down, so that the rollers 61 get free of the cams 18_a and 18_b and allow thus the displacement of the shaft 114. In order that this movement downwards of the levers 166 may be effected without being met with too great a resistance from the pump plungers, these latter are provided in a similar way to that described with reference to the constructional forms shown in the previous figures with a relieving gear comprising a by-pass valve or by-pass slide inserted in the pressure piping of each separate pump and connected with the common starting handle in such a way that the pumps are relieved of pressure when the starting handle is in its stop or start position. As mentioned above, this latter handle is locked in such a way in relation to the reversing motion that it may only be moved when the reversing apparatus is in any of its outermost positions, and similarly the reversing gear can only be moved or manipulated when the starting handle is in its stop position, whereby is obtained that the fuel pump is relieved of pressure before the reversing shaft can be moved, so that the reversing may be done in the easiest possible way. In the constructional forms of the invention shown in Figs. 3, 7 and 8 the valve, slide or the like serving when open to relieve the fuel pump during the reversing period is shown built into the housing of the fuel pump, so that its opening is effected from the engine platform by means of rod and link connections or the like. In certain cases it may be advantageous, however, that this valve or its equivalent is so disposed that it may be reached directly from the engine platform; in this case it may be mounted as a separate unit connected with the pressure chamber of the pump by a pipe. Such pipe will, however, increase the total volume of the pressure chamber, the elasticity of which will give rise to an inexpeditiously great amount of lagging in the system. To avoid this drawback the piping is pro-

vided with a non-return valve situated very close to or inside the pump housing. In a multiple-cylinder engine this arrangement may be effected in such a way that said pip-
5 ings are joined into a single line, so that one overflow valve may serve all the fuel pumps during the reversing. In the constructional form of an arrangement of this kind, as em-
ployed in a four-cylinder engine, shown dia-
10 grammatically in Fig. 10, 101_a—101_d indicate the four fuel pumps which during normal running of the engine pump the fuel through the pressure pipes 102_a—102_d to the fuel valves. 103_a—103_d indicate spring-in-
15 flenced non-return valves preventing the fuel from flowing backwards from the pipes 104_a—104_d into the fuel pumps. The pipes 104_a—104_d are joined into a common pipe 105 which is provided at its one end with an over-
20 flow, control, or safety valve 106, or a slide or the like, which is normally closed but is lifted by a lever 108 connected by a tension rod 109 with the starting handle, when the latter is set for stop or starting, whereby the
25 fuel oil is returned to the fuel oil tank through a pipe 107.

The invention is not bound to the constructional forms above described and set forth, which are only intended to serve as examples, 30 and the invention may be carried out in several different ways without thereby departing from its principles.

I claim:

1. A reversing gear for combustion engines in which fuel is injected into the cylinder without compressed air being employed and by pressure from a pump, the motion of which is positively controlled with relation to the piston strokes of the engine by a reversible cam mechanism comprising a shaft, a plurality of cams on said shaft, a plurality of levers, cam rollers on each of said levers adapted to cooperate with said cams, a fuel pump connected to one of said levers and means raising during reversal of direction the cam roller on the lever cooperating with the fuel pump clear of the cams in a direction coinciding with its normal direction of motion and means for relieving said fuel pump mechanism of pressure during the reversal, said latter means being controlled by the starting handle of the engine and actuated when the handle is moved to the stop position.
2. A reversing gear as set forth in claim 1, in which the starting handle is connected to the reversing shaft in such a manner that they lock each other so that the rotation of the reversing shaft is possible in only one position of the starting handle whereby the relief of the fuel pump mechanism is effected before reversal is possible, and the motion of the starting handle out of the stop position is possible only in one position of the reversing shaft.

3. A reversing gear for combustion engines in which fuel is injected into the cylinder without compressed air being employed and by pressure from a pump, the motion of which is positively controlled with relation to the piston strokes of the engine by a reversible cam mechanism comprising a shaft, a plurality of cams on said shaft, a plurality of levers, cam rollers on each of said levers, adapted to cooperate with said cams, a fuel pump connected to one of said levers and means raising during reversal of direction the cam roller on the lever cooperating with the fuel pump clear of the cams in a direction coinciding with its normal direction of motion and means for relieving said fuel pump mechanism of pressure during the reversal of direction, said latter means being controlled by the starting handle of the engine and actuated when the handle is moved to the stop position, said fuel pump having a releasing valve therein and means actuated by said starting handle when moved in the starting position for opening said valve during the reversal.

4. A reversing gear according to claim 1 in which the cam mechanism by which the motion of the fuel pump plunger is effected comprises a spring pressed during the normal working of the engine at the compression stroke, the inward stroke of the pump plunger, and which causes thereafter the outward stroke of the pump plunger, whereby the said spring causes no resistance against the respective cam rollers.

5. A reversing gear according to claim 1 and in which the inward motion of the fuel pump plunger during the normal working of the engine is effected by a lever carrying in a suitable place the spring device causing the outward motion of the pump plunger, comprising a fixed stop against which the lever is pressed during the reversal by means of the spring mechanism so that the stop serves as a support for the lever during its rotation caused by the cam roller being raised clear of the cam.

6. A reversing gear according to claim 1, and in which the motion of the pump plunger from the cam is effected by a lever having a fixed axis of rotation, in which the lever is provided with a branch, projecting arm, or notch, which during the reversal is influenced by an eccentric, on the reversing shaft moved by a suitable eccentric linked connection together with the reversing shaft, so that the cam roller is raised away from the cam against the resistance of the spring normally keeping the roller against the cam.

7. A reversing gear according to claim 3 and in which the releasing valve contained in the pump mechanism is connected with the pump piston, said connection comprising a lever connected also with the starting handle of the engine by a link mechanism in such a

way that the axis of rotation of the lever may be displaced, so that the releasing valve is opened when the starting handle is set for stop or start.

5. 8. A reversing gear according to claim 3 in which a slide with an oblique shaped overlap is employed to control the injection period, the said slide being rotatable around its axis and its rotation being effected from the 10 starting and controlling handle of the engine by means of a suitable link mechanism so that the slide uncovers an overflow passage in the pump apparatus, when the starting handle is positioned for stop or start.
15. 9. A reversing gear for combustion engines in which fuel is injected into the cylinder without compressed air being employed and by pressure from a pump, the motion of which is positively controlled with relation to the 20 piston strokes of the engine by a reversible cam mechanism comprising a shaft, a plurality of cams on said shaft, a plurality of levers, cam rollers on each of said levers, adapted to cooperate with said cams, a fuel 25 pump connected to one of said levers and means raising during the reversal of direction the cam roller on the lever cooperating with the fuel pump clear of the cams in a direction coinciding with its normal direction of 30 motion, and means for relieving said fuel pump mechanism of pressure during reversal of direction, a locking disk having a pawl cooperating with a pin on the starting handle of the engine, a gear mechanism connecting said 35 reversing shaft to said disk whereby only one position of the disk permits the engagement and any other position of the disk causes the handle to be maintained in its stop position.

In testimony whereof I affix my signature.
